UNITED STATES PATENT OFFICE.

HERBERT GUETTLER, OF ESCANABA, MICHIGAN, ASSIGNOR, BY MESNE ASSIGNMENTS, TO FIBER MAKING PROCESSES, OF CHICAGO, ILLINOIS, A CORPORATION OF ILLINOIS.

BARKING APPARATUS.

Application filed June 4, 1915. Serial No. 32,047.

To all whom it may concern:

Be it known that I, HERBERT GUETTLER, a subject of Hakon VII, King of Norway, and a resident of the city of Escanaba, Delta 5 County, Michigan (which is his post-office address), have invented certain new and useful Improvements in Barking Apparatus; and I do hereby declare the following to be a full, clear, and exact description of 10 the invention, such as will enable others skilled in the art to which it appertains to make and use the same.

This invention relates to bark removing machines of the type in which blocks of 15 wood from which the bark is to be removed are tumbled in a rotating drum in the presence of water. In machines of this type the lower portion of the drum extends into a water tank and is usually supported upon 20 rollers or wheels mounted in bearings positioned within the tank underneath the drum. These rollers and bearings form obstructions to the free removal from the tank of the detached pieces of bark and furthermore 25 there is a tendency for the pieces of bark to accumulate and become packed together at these points, thereby preventing free rotation of the drum. One of the objects of this invention is to so support and rotate 30 the drum that the surface of the tank upon which the pieces of bark are received will be unobstructed throughout its entire extent.

Other features of the invention consist 35 in providing adjustable retaining means at the ends of the drum for varying the amount of wood which may be contained therein and for varying the angle of inclination assumed by the surface of the wood when the drum is rotating.

40 Means are also provided for varying the level of the water within the tank in accordance with the amount of wood within the drum, the object being to provide a quantity of water which will be sufficient to keep the

45 wood soaked down but which will be just enough to prevent the wood from floating. By thus regulating the amount of water, it will serve as a support for the wood, thereby relieving to a great extent the pressure 50 exerted by the weight of the wood upon the mechanism for supporting and rotating the drum.

In the accompanying drawings, showing an embodiment of the invention,

Figure 1 is a view of the improved bark- 55 ing machine in side elevation;

Fig. 2 is a sectional view on the line 2-2 of Fig. 1;

Fig. 3 is a plan view;

Fig. 4 is an end elevational view as seen 60 from the right of Fig. 1; and

Fig. 5 is a detail sectional view on an enlarged scale.

Referring to the drawings, the embodiment of the invention shown comprises a 65 drum 1, preferably cylindrical and open at both ends and adapted to be rotated in a tank 2 adapted to contain water and having a concave bottom 3 concentric with the drum.

The drum is supported and rotated by 70 endless chains 4 which engage rings 5 circumferentially secured to the drum and which pass over sprocket wheels 6 and 7 supported upon a suitable frame 8. The 75 sprocket wheels 6 are secured to independent axles 9 which are journaled in take-up bearings 10 of any approved type by means of which the slack of any chain may be taken up, thus insuring that the load will be 80 evenly distributed with respect to the several chains. The sprocket wheels 7 are mounted upon a common shaft 11 journaled in bearings 12 and to this shaft is secured 85 a sprocket wheel 13 adapted to be driven from a line shaft or other suitable source of power by means of a chain 14. The surfaces of the rings 5 with which the chains 4 engage are smooth in order that the chains may slip thereon if any obstruction should 90 prevent rotation of the drum.

In order to prevent lateral swinging or 95 upward jumping of the drum during its rotation, it is provided, adjacent its ends, with guide rings 15 having flanges 16 which engage grooved guide rollers 17 rotatably mounted upon the frame at the sides and top of the drum.

The blocks of wood from which the bark is to be detached are introduced into one end 100 of the drum by means of a chute 18, and, after the bark has been removed, are delivered from the other end of the drum over a chute 19 into a runway 20 from which they may be removed in any suitable manner. The drum has a plurality of openings 21 formed in its side which are of 105 such a size that the pieces of detached bark

may pass freely therethrough into the tank without permitting the escape of any of the blocks.

Secured to the outer surface of the drum 5 are a plurality of paddles or flights 22, preferably perforated, which, as the drum rotates, sweep through the water in the tank 2 and remove therefrom the pieces of bark which have passed into the tank through the 10 openings 21 in the drum. The pieces of bark which are swept from the bottom of the tank by the paddles will be discharged through an opening 23 formed in one of the side walls of the tank, and may be received 15 in any suitable receptacle such as a drain 24 from which they may be removed and treated as desired to render them suitable for fuel or other industrial purpose.

By supporting the drum upon chains as 20 above described, it is possible to do away with the usual drum supporting rollers which are mounted within the tank, thereby insuring that the bottom of the tank will be smooth throughout its entire extent and 25 will be free from any obstructions which might interfere with the removal of the bark or the free rotation of the drum.

As the drum rotates, the charge of wood contained therein will be also rotated until 30 its upper surface assumes a certain angle as indicated in Fig. 2, after which the blocks of wood will tumble downward over one another, and this tumbling of the blocks upon one another, which continues during the rotation of the drum, is sufficient to cause the bark to become detached. The quantity of wood which may be treated, and consequently the angle of inclination which the surface 35 of the charge will assume during the operation, depends upon the quality and character of the wood. In order that the machine may be adapted to treat different quantities of wood, adjustable means are provided adjacent the open ends of the drum to vary 40 the height of the wood which may be retained within the drum. As shown, the ends of the frame are provided with vertical guideways 25 which are adapted to receive transversely extending planks 26, the 45 guideways being so positioned that when the planks are positioned therein they will register with the open ends of the drum and will be in close proximity thereto. It will be understood that the level of the charge 50 of wood which the drum will hold will depend upon the number of planks which are placed one upon the other within the guideways.

The amount of water within the tank 2 55 should also be varied in accordance with the quantity of wood contained within the drum in order that there may be sufficient water within the tank to keep the wood thoroughly soaked down, without, however, permitting it to float. By so proportioning the amount

of water to the quantity of wood being treated, the water acts as a support for the wood and relieves to a great extent the weight which the chains 4 must otherwise support. In order to vary the amount of water within the tank, planks 27 are positioned within the opening 23 which planks extend throughout the length of the opening and are held in place by having their ends engage in suitable guideways 28. These planks form a dam extending upward from the lower edge of the opening by means of which the level of the water within the tank may be varied, the height of the dam depending, of course, upon the number 75 of planks which are employed.

What I claim is:

1. In a bark removing machine, the combination of a rotatable drum adapted to continuously receive blocks of wood at one end and to discharge them at the other end, said drum having bark discharging slots, a tank adapted to contain water wherein the drum may rotate, said tank having a concave bottom which throughout is substantially concentric with the drum, endless chains supporting the drum, and means carried by the drum for continuously removing the bark from the tank as the drum rotates. 85

2. In a bark removing machine, the combination of a rotatable drum open from end to end and adapted to continuously receive blocks of wood at one end and to discharge them at the other end, said drum having longitudinal bark discharging slots, a tank adapted to contain water wherein the drum may rotate partly submerged to periodically submerge the wood under treatment, said tank being unobstructed from end to end and having a concave bottom which throughout is substantially concentric with the drum, and means carried by the drum for continuously removing the bark from the tank as the drum rotates. 90

3. In a bark removing machine, the combination of a rotatable drum adapted to continuously receive blocks of wood at one end and to discharge them at the other end, said drum having a plurality of longitudinal bark discharging slots, a tank adapted to contain water wherein the drum may rotate partly submerged to periodically submerge the wood under treatment, said tank having a concave bottom substantially concentric with the drum, means supporting said drum from above, means for continuously rotating said drum, and means carried by the drum for lifting the bark over the edge of the tank as the drum rotates. 100

4. In a bark removing machine, the combination of a rotatable drum adapted to continuously receive blocks of wood at one end and to discharge them at the other end, said drum having bark discharging slots in its side, a shallow tank adapted to contain 105

- water wherein the drum may rotate partly submerged to periodically submerge the wood under treatment, said tank having a concave bottom which throughout is substantially concentric with the drum, said tank being unobstructed from end to end, endless chains supporting and continuously driving the drum, guide rings secured to the outer surface of the drum, rollers engaging the guide rings, and means carried by the drum for continuously lifting the bark over the edge of the tank as the drum rotates. 5
5. In a bark removing machine, the combination of a rotatable drum open from end to end and adapted to continuously receive blocks of wood from which the bark is to be removed, said drum being provided with longitudinal bark releasing slots and a plurality of encircling rings; a shallow tank 10 adapted to contain water wherein the drum may rotate partly submerged, said tank being unobstructed from end to end and having a concave bottom substantially concentric with the drum on both sides, endless chains engaging the rings and supporting and continuously driving the drum, and means carried by the drum for continuously removing the bark from the tank as the drum rotates. 15
- 20 6. In a bark removing machine, the combination of a rotatable drum adapted to receive blocks of wood, a tank adapted to contain water wherein the drum may rotate, an adjustable dam along one side of said tank 25 to vary the level of the water within the tank and means for lifting the separated bark over said dam. 30
7. In a bark removing machine, the combination of a rotatable drum adapted to receive blocks of wood at one end and to discharge them at the other, a tank adapted to contain water wherein the drum may rotate, said tank being concentric to said drum, throughout, and having an opening in one 35 of its walls to determine the normal level of the water contained therein, means co-operating with said opening to vary the level of the water within the tank and means for lifting the bark in said tank and discharging it through said opening. 40
8. In a bark-removing machine, the combination of a rotatable drum open from end to end, having bark-discharging slots along its sides and being adapted to continuously 45 receive through one end the blocks of wood from which the bark is to be removed, and to continuously discharge the clean blocks through the other end, flights in said drum for tumbling the wood, means for continuously rotating said drum, a shallow tank 50 adapted to contain water wherein the drum
- may rotate partly submerged to periodically submerge the wood under treatment, said tank being concentric with said drum and unobstructed from end to end and having an opening in one of its walls to determine the normal level of the water contained therein, means to close the lower portion of said opening to raise the level of the water which the tank may contain in accordance with the weight and quantity of the wood under treatment, so that the wood may be thoroughly soaked without floating, and means for continuously and progressively removing the separated bark from said tank. 55
9. In a bark removing machine, the combination of a rotatable drum open at both ends and adapted to receive a charge of blocks of wood, a tank adapted to contain water wherein the drum may rotate, adjustable retaining means adjacent the ends of the drum and co-operating therewith to vary the amount of the charge which the drum will hold, and adjustable means to vary the level of the water in the tank in accordance with the amount of wood in the drum, whereby for any charge the wood will be properly soaked down but will be prevented from floating. 60
10. In a bark removing machine, the combination of a rotatable drum adapted to continuously receive blocks of wood at one end and to discharge them at the other end, said drum having longitudinal bark discharging slots, a tank adapted to contain water wherein the drum may rotate partly submerged to periodically submerge the wood under treatment, said tank being unobstructed from end to end and having a concave bottom which throughout is substantially concentric with the drum, and means carried by the drum for continuously removing the bark from the tank as the drum rotates. 65
11. In a bark removing machine, the combination of a rotatable drum adapted to continuously receive blocks of wood from which the bark is to be detached, a shallow tank adapted to contain water wherein said drum may rotate, said tank being throughout substantially concentric with said drum and free from bark retaining corners, means for revolvably supporting said drum from outside said tank, a compartment adjacent to said tank, means for continuously rotating said drum and means for continuously delivering the detached bark over the edge of said tank into said compartment. 70
- In testimony whereof I affix my signature.
- HERBERT GUETTLER.
